METHOD OF MOUNTING THE ELECTRODE SYSTEM FOR ELECTRIC DISCHARGE TUBES

Leonard Klinkert, Gerard Charles Antonie Marie Moubis, and Johan Lodewijk Hendrik Jonker, Eindhoven, Netherlands, assignors to Hartford National Bank and Trust Company, Hartford, Conn., as trustee

Application July 24, 1947, Serial No. 763,190
In the Netherlands August 7, 1946

2 Claims. (Cl. 29—25.14)

1

This invention relates to a method of mounting the electrode system for electric discharge tubes and to electric discharge tubes comprising such a system.

As a rule, an electrode system is mounted in such manner that at first a centering member is laid in a holder and, subsequently, the electrodes are successively placed, at one extremity, in the apertures of the said centering member, whereupon the other extremities of the electrodes are introduced into a second centering member. During this operation the extremities are pushed to and fro till they engage in the corresponding apertures of the second centering member, whereupon the latter member is slipped on the electrode extremities. However, moving the extremities to and fro in order to make them engage in the said apertures takes much time and requires much routine whilst involving the danger of the supporting wires and electrodes being bent. More particularly the lower grid turns are in this case frequently damaged.

The said difficulty may be somewhat reduced by providing that the extremities of the supporting wires are of different lengths to enable them to be introduced successively into the associated apertures, but in this case also the danger of damage of the electrodes is considerable, especially also on account of the fact that the electrodes, instead of being pinched at one extremity, are loose in the apertures of the first centering member. The electrodes are thus unstable and may consequently contact with one another and be damaged.

It is an object of the invention to provide a method and means which simplify the mounting of the electrode system and which permit to avoid the above described inconveniences.

It is another object of the invention to provide a method and means for temporarily securing both ends of each electrode during the mounting operation so as to prevent them from becoming displaced or damaged.

Other objects and advantages of the invention will become apparent from the following description.

According to the invention, the electrodes to be mounted are first placed with one extremity in the apertures of a centering member and clamped, for instance below that centering member by pinching means more fully described herein below. The other electrode ends are aligned with the apertures of a second centering member in position to be introduced into said apertures. For the purpose of aligning these ends

and holding them in position while the second centering member is slipped thereon, a centering jig is used which has two jaws cooperating with each other for holding said ends in place.

5 In one embodiment of the invention which is exemplified in the following with reference to the accompanying drawing, the upper extremities of the electrodes are pinched in position between toothed jaws of a centering jig, which is removed after the extremities have been introduced into the corresponding apertures of the upper centering member, whereupon the said member may be slipped on the electrode extremities. Moreover, the electrodes are pinched also at the lower extremities, for example at the extremities projecting below the lower centering member preferably, a short time before the toothed jaws engage the upper extremities. Owing to the fact that the electrodes are maintained rigidly pinched at the lower extremities and are no longer unstable, there is less danger that the teeth of the jaws may not engage the electrode extremities. Since, after the electrodes have been pinched in position, the upper extremities may be introduced without difficulty into the corresponding apertures in the upper centering member, the danger of damage of the electrodes is small.

The invention will now be explained more fully by reference to the accompanying drawing, in which:

Figure 1 shows an arrangement of an assembly jig according to the invention, and

Figure 2 shows a detail of such a jig.

In Figure 1, reference numeral 1 designates a holder consisting of a thin plate which comprises a recess to accommodate the lower centering member 2, as a rule in the shape of a mica disc. The holder 1 is secured to a stand 7. The lower extremities of the electrodes 3 are introduced into the apertures of the member 2 and may be pinched in position at the portions projecting below member 2 by means of a pinching device. Subsequently, the jaws 4 and 5 are closed whereby the upper extremities of the electrodes 3 are fixed in position in a centered manner to enable them to be introduced without difficulty into the apertures of the upper centering member 6, whereafter the jaws 4 and 5 are removed. Next, the member 6 is slipped on the electrode extremities and fixed in position in the usual manner. Although each of the jaws 4 and 5 may be provided with a toothed edge, it generally suffices if one of the jaws exhibits a toothed edge and the other a straight one.

The electrode extremities projecting below the lower centering member may be pinched in position by means of a rubber pinch, but preferably by means of a pinching device of the type shown in the figures.

The stand 7 exhibits a plane portion 8, provided in such manner that, when it is engaged by the electrode extremities 14, the electrodes extend vertically through the apertures of the holder 1 and the centering member 2. By means of an arm 9 having a knife-shaped edge 11, the electrode extremities 14 are immovably urged against the plane 8, the knife-edge 11 slightly cutting into the extremities of the supporting wires. The movement of the arm 9 is determined by the abutment 12 and is adjustable by means of an adjusting screw 13. The electrodes are immovably held in position by the knife 11 also in the vertical direction so that the lower grid turns no longer run the risk of being damaged by pressure exerted on the upper extremities of the electrodes when the upper centering member is slipped thereon. Owing to the fact that the knife-edge 11 cuts into the supporting wires 14, the pinching operation cannot be affected by differences in the thickness of the supporting wires.

It was known per se to lay electrodes in the horizontal position in toothed templets and, subsequently, to pinch them in position and to provide from the side milled centering members consisting of two parts. In this case, however, one is limited to the use of centering members consisting of two parts. The difficulties involved in the conventional method of mounting in connection with slipping the centering members on the electrode extremities do not, however, occur in this method, so that this method cannot be used to solve the said difficulties.

What we claim is:

1. A method of assembling an electrode system for an electric discharge tube in two centering members having apertures for receiving the ends

of said electrodes, comprising the steps of placing one end of each electrode in the apertures of one of said centering members, clamping and cutting into each of the assembled ends of the electrodes to rigidly hold them against displacement in vertical and horizontal directions, aligning the other ends of said electrodes in position for entering the apertures of said other centering member, temporarily clamping said other electrode ends to hold them rigidly in said aligned position, and sliding said second centering member over said aligned other ends.

2. A device for assembling an electrode system for an electric discharge tube in two centering members having apertures for receiving the ends of said electrodes, and a support for said first centering member, said support including clamping means for rigidly holding one of the ends of the electrodes against vertical and horizontal displacement, said clamping means comprising a plane-faced element and a knife-like element adapted to cut into the electrodes and rigidly clamp them against the plane-faced member.
